INVENTOR
William H. Smith,
BY
R. Baldwin Hale
ATTORNEY

UNITED STATES PATENT OFFICE.

WILLIAM H. SMITH, OF SAN FRANCISCO, CALIFORNIA.

BINDER FOR LOOSE LEAVES.

Application filed August 2, 1926. Serial No. 126,415.

This invention relates to improvements in "binders" for loose leaves, and more particularly to transfer binders, and consists of a novel construction and combination of the parts. Among the objects of this invention, are to produce a binder in this class, that exposes no exterior metal parts liable to injure the hands of the operator or scratch and mar polished desk tops upon which the bound books may be laid; that will present no protruding parts upon any of the exterior surfaces of the binding to interfere with its compact storage in the minimum of space or inconvenience in inserting and withdrawing it from between other volumes of similar nature; that may be cheaply and conveniently produced and that is easily adaptable to the binding of sales sheets, bills of lading, stock records, proof sheets, invoices, ledger sheets, and other perforated sheets used, and known as loose leaf record sheets; and that is easily loaded with sheets to be bound without extraneous mechanical aids. Other objects and advantages will appear as this description progresses.

In this specification and the annexed drawings, the invention is disclosed in the form considered the best, but I do not wish to be understood as limiting the invention to this form, as it may be embodied in other forms, and it is also to be understood that in and by the claims following the description it is desired to cover the invention in whatsoever form it may be embodied.

In the accompanying one sheet of drawings, Figure 1 is a side elevation of a binder constructed in accordance with this invention, one of the binding posts being shown in fragmentary section and extending through perforations in the sheets, to form the bound back of the book; the mass of leaves are indicated in outline by the dotted lines. Figure 2 is a fragmentary perspective view of the lower cover, partially broken away to show the construction of the cover and the application of the "kraft" paper tube and ferrule adapter to fit various sizes of leaf perforations. Figure 3 is a plan view of the inside of a cover in the process of fabrication, in accordance with the method of this invention. Figure 4 is an enlarged detail edge view of the same after completion. The channel is partially broken away through the perfora-

tion to illustrate the position of the perforated plate overhanging the unperforated 55 plate of the channel.

In detail the construction illustrated in the drawings, see Figure 1, comprises the covers 1 and 2 that are alike in general construction. They are composed of the boards 3, 60 consisting of rectangular pieces of backing board of the desired dimension. This board 3 is covered with any suitable binding material, such as leather, and the various imitations thereof, buckram, or the like. This binding fabric 4 is glued to the outer surface of the board and lapped over the outer ends and the sides as at 5, and glued to the inner surface of the board. The binding 4 and the folds 5, are extended beyond the back edge 70 of the board and a strip of sheet metal 6, is inserted with its ends under the folds 5, and its edge 7 parallel with and spaced from the edge 8 of the backing board cover, so that the cover and fold 4 and 5 form a flexible 75 hinge strip at 9.

The further extensions of the binding 4, are then glued together to form a double thickness of the fabric, enclosing the strip of metal 6, and extending around the outer edge 10 of the metal strip 6 and glued, to entirely enclose the metal strip, and terminates as at 11 making a double thickness at the hinge 9. While the metal strip is still flat it is inserted between the dies of a punching machine (see Figure 3) equipped with proper gages to determine the exact centers between the perforations 12, which are cut entirely through the metal strip and the overlying binding 4, enclosing the same. After 80 the punching operation the metal strip is inserted between the jaws of a breaker and it is bent back upon itself at 13, to form a U shaped back edge for the cover, the outer dimensions of which are substantially the same 85 as the thickness of the cover, and forming the channel 14, the edge 10 terminating adjacent to the line of the hinge 9. The perforations 12, thus appear only upon the inner flanges of the channels. The inner surfaces 100 of the covers are finished by the addition of a sheet of heavy paper 15, or other suitable material pasted to the cover and overlapping the folds 5 and the ends 11. As previously stated both covers 1 and 2 are identical in 105 shape and construction and may be of any di-

mensions to suit standard or special sizes of loose leaves to be bound therebetween.

The binder posts consist of two lengths of tubing 15—16 telescoping snugly one within the other, and both flanged out to engage the integral heads 18. The tube 15 has a hole at 19 in the body thereof, adjacent its end, with the slot 20 opposite thereto. The pawl 21 is confined within this tube with its toothed surface adapted to protrude through said slot 20. The pawl is retained in position by the spring 22 confined between the pawl 21 and a plug in the end of the tube 15. When the tubes 15—16 are telescoped the teeth of the pawl 21 contact the inner surface of the tube 16 without resistance, but when it is attempted to separate the tubes, the teeth of the pawl engage the inner surface of the tube 16, locking the tubes together, forming in effect a positive clutch.

The perforations 12 have the enlargements 12' opening therefrom, adapted to pass the heads 18 of the posts. The posts 15—16 are then forced into the smaller openings 12 and are firmly held by the heads 18, within the channel 14 formed by the metal strip 6. These perforations 12 are spaced apart any of the standard distances, ranging from $2\frac{3}{4}$ to 7 inches between centers that are standard practice, or they may be spaced apart any desired distance.

This invention operates substantially as follows: The covers 1 and 2 are laid face up, as shown in Figure 2, the heads 18 of the various binder posts 15—16 are inserted in the openings 12' in the covers. The cover 1 is then laid aside for the moment and the perforated leaves X are threaded onto the posts in the cover 2, up to near the top of the posts 15; then the remaining leaves, up to the capacity of the posts are threaded onto the posts 16 that are in the cover 1. The cover 1 is then inverted over the cover 2 and the posts in the cover 1 are telescoped over the posts in the cover 2, the telescoping tubular posts 15—16 extending through the perforations in the leaves X. As the top posts 16 are forced down over the lower posts 15 the two sections are locked by the clutch 21, against retraction. The necessary pressure is then exerted on the top cover, opposite the posts, to cause them to compress the leaves between to the desired extent, which effectually binds all of the leaves into a single volume having a smooth exterior covered by the covers 1 and 2 and securely and permanently bound together at the back by the posts 15—16. The covers 1 and 2 freely swing on their respective hinges at 9 to permit access to the leaves bound between the covers.

To add a proper finish to the back of the book, between the covers 1 and 2 I provide the overlapping backing sheets 23 and 24, scored longitudinally at the points 25 to 65 permit of easy and accurate bending at this

point and forming the right angle flange 26 thereon. This backing is preferably made of heavy "kraft" paper, gummed on one side, the two halves of the backing being threaded onto the posts in their respective covers 1 and 2, and projecting outward past the ends 13 thereof, until the binding of the leaves X is complete. The inner surface of the backing 23 is moistened and forced against the outer surface of the backing 24, pressure against the backing forcing it against the end of the bound sheets causes the backing sheets 23 and 24 to adhere and form a permanent surface for the reception of tubulated matter indicating the contents of the book. 80

The various manufacturers of the so called "loose leaf systems" of bookkeeping and record sheets, adopt certain arbitrary standards as to the size and shape of the perforations in the binding margins of the sheets, 85 the diameters of such perforations ranging from the small diameter of the posts 15—16 up to one-half an inch. Since it is impracticable to meet these variations in transfer binders within the price of such, recourse is 90 had to the expedient shown in Figure 2, in which a fragmentary section of the paper tube 27 made of heavy "kraft" paper rolled upon itself to fit the size of the perforation in the sheet to be filled and snugly fit over 95 the posts 15—16 is chosen and cut to a length equal to the depth of sheets, see Fig. 1, to be bound between the covers 1 and 2; in this manner cheaply adapting this invention to the wide range of conditions to be met in the 100 perforations of loose leaf sheets at present upon the market.

While the form of posts shown in the drawings and above described is at present preferred, because of its simplicity, adaptability 105 and cheapness of production, there are other forms of posts at present upon the market, such as, parallel semi-circular ratchet-posts and other forms of telescoping posts, in which one-half of the post is tubular to receive the shank of the complementary post, telescoping therein and secured by various forms of clutches to prevent withdrawal or separation of the post sections from each other, as well as wires and other connecting 110 means adaptable to this invention.

For convenience in withdrawing a bound volume from among others on the shelves, the length of tape 26 is glued to the inner flange with its end folded over the edge 10 and terminating within the channel 14, and its opposite end extending beneath and beyond the backing 23 to form the tab 31, to be grasped by the operator in withdrawing the volume. 120

Having thus described this invention, what I claim and desire to secure by Letters Patent is:

1. A transfer binder comprising opposed covers having channels hinged to the edges thereof; binding means extending between 130

5 said channels and adapted to engage the inner plates thereof and terminating within said channels; backing sheets attached to each of said covers adapted to be overlapped and attached to each other when the binder is filled; and a strip of tape having an end secured to one of said covers protruding beyond said binder.

10 2. A transfer binder comprising opposed covers having channels hinged to the edges thereof; binding means extending between said channels and adapted to engage the inner plates thereof and terminating within said channels; backing sheets attached to each of said covers adapted to be overlapped and attached to each other when the binder is filled; and a strip of tape having an end secured to one of said covers protruding beyond said binder.

15 20 3. A cover for transfer binders comprising a stiffening board; a binding fabric having its lateral edges folded over the edges of said board and extending beyond one end of said board to form a hinge; a metal channel hinged to said board by said binding fabric, the inner plate of said channel being perforated; and a binder post having a shank passing through said perforation in, and a head engaging under, said plate.

25 30 4. A cover for transfer binders comprising a stiffening board; a binding fabric having its lateral edges folded over the edges of said board to form a hinge; a strip of metal enclosed within said folded edges and bent back

upon itself to form a channel, one plate of said channel being perforated to receive a binder post.

5. A cover for transfer binders comprising a stiffening board; a binding fabric having 40 its lateral edges folded over the edges of said board and extending beyond one end of said board to form a hinge; a strip of metal enclosed within said folded edges and bent back upon itself to form a channel flush with the 45 thickness of said cover, said binding fabric terminating at the open edge of said channel.

6. A transfer binder comprising opposed covers each having a channel hinged to an edge thereof; binding means extending between said channels and adapted to engage the inner plates thereof and terminating within said channels; flexible adhesive backing sheets attached to each of said covers and adapted to be overlapped with respect to each 55 other when the binder is filled.

7. The method of forming covers for transfer binders comprising folding the adhesive edges of a binding fabric over the lateral edges of a stiffening board so that it extends 60 beyond the end of said board; inserting a transverse strip of metal beneath said folded edges and spaced away from the end of said board; perforating said strip and fabric to engage binder posts; and then bending said 65 strip back upon itself to overlie its unperforated part.

In testimony whereof I have hereunto affixed my signature.

WILLIAM H. SMITH.
